UNITED STATES PATENT OFFICE.

THOMAS F. KELLY, OF GALION, OHIO.

BURIAL-VAULT.

No. 878,962.

Specification of Letters Patent.

Patented Feb. 11, 1908.

Application filed April 29, 1907. Serial No. 370,883.

To all whom it may concern:

Be it known that I, THOMAS F. KELLY, citizen of the United States, residing at Galion, in the county of Crawford and State of Ohio, have invented certain new and useful Improvements in Burial-Vaults, of which the following is a specification.

This invention relates to burial vaults or metallic cases used to inclose caskets, and has for its object to provide improved means for locking the cover of the case onto the body thereof, as well as improved means for forming a tight joint therebetween, when the cover is put in place.

15 The locking devices are applied to the inside of the case, so that when the cover is once put on and the said devices engaged, they cannot be unlocked, and the cover consequently then cannot be removed.

20 The invention is illustrated in the accompanying drawings, in which Figure 1 is a side elevation of the case. Fig. 2 is a vertical cross section.

25 The body of the case is indicated at 6, and the cover at 7. These parts are preferably made of sheet steel or the like, pressed or built to proper shape.

30 A trough around the outside of the edge of the case is produced by means of a V-shaped strip or plate 8 which is riveted, as at 16, at its inner upper edge, to the body of the case and which extends around all sides thereof. The rivet is concealed and inaccessible from the outside. The outer side of this trough 35 inclines away from the upper edge of the case, and said side has at its upper edge a horizontally-projecting flange 10.

30 At 11 is indicated a flange extending around the outside of the sides of the cover, and positioned opposite to the flange 10, to which it is or may be connected by bolts 12. On the inside, the side walls of the cover have a continuous hooked flange or plate 13, the hook being formed by bending up the lower edge of the plate, which is secured at its upper edge to the cover by the rivets or bolts 17 of the cover handles 18, whereby said rivets are concealed and inaccessible from the outside.

50 The body of the case is provided on the inside of the side walls with a series of spring hooks 14, which are secured thereto by the rivets or bolts 16, and at their lower ends by

the rivets or bolts 19 of the body handles 20. These hooks project above said wall in position to snap over the hooked flange 13 when the cover is pressed down into place. And when so engaged it is impossible to unlock said hooks.

55 The plate 8 forms, as stated, a trough into which the lower edge of the cover projects and is sealed by means of a composition indicated at 15, which may be melted lead, soft metal of other kinds, or rubber, forming a water and air tight joint.

60 In use, the coffin is placed in the case and the cover is then put on. It may be put on at either side first, and if engaged first at one side the engagement of the other side is not prevented, being in this respect distinguished 70 from some vaults in which the whole cover has to be closed at all sides at once, or it will not lock. After the cover is put on pressure is applied by means of the bolts 12 to force the edge of the cover into the packing 15, 75 until the hooks on the inside are engaged, which locks the cover in place. All the rivets or bolts of the locking devices being concealed, no opportunity is afforded for access to the case by extracting the rivets.

80 I claim:

1. A burial vault comprising a case, a trough extending around the upper edge thereof, the inner side of the trough being bent up and having fastenings to the wall of the case above the bottom of the trough, so that the fastenings are inaccessible from the outside, a cover the edge of which projects into the trough, and interior fastening devices between the cover and the case.

90 2. A burial vault comprising a case having spring hooks projecting above its edge on the inside, a cover having on the inside a flange engageable by the hooks, handles on the outside of the case and cover respectively, said handles having bolts extending through the case or cover and engaging the hooks and flange respectively and fastening the same in place.

95 In testimony whereof I do affix my signature, in presence of two witnesses.

THOMAS F. KELLY.
